UNITED STATES PATENT OFFICE

2,325,383

SINGLE DRUM LOCOMOTIVE BOILER

George H. Emerson, Baltimore, Md.

Application November 24, 1941, Serial No. 420,296

4 Claims. (Cl. 122—94)

My present invention is an improvement on a single drum locomotive boiler disclosed in my Patent No. 1,869,309, dated July 26, 1932.

By reason of the invention disclosed in that patent I was enabled to reduce the number of drums employed in the top of the fire box to a single drum, thereby providing a simpler, stronger and more durable type of fire box without sacrificing steam generating and water circulating efficiency. This is due, in that construction, to the fact that there are less heat losses and that a concentration of the heat and better heat transfer are obtained, notwithstanding the reduction of the number of drums with reduced resistance to circulation, allowing a better and more rapid circulation of the water. The arrangement described in my patent above named of the upper headers and their direct connection with the sides of the single drum assures a very rapid and violent circulation of the water between the headers and the drum. This results in a very highly efficient breaking up of the water in the vertical circulating tubes into relatively small particles, each surrounded by a relatively large effective heating surface whereby very quick steaming is obtained, and such violent circulation in turn acts as a safety factor as the part of the drum (equivalent to the crown sheet of an ordinary boiler) in contact with the fire, will always be covered with water even through the water level in the boiler tends to actually fall below the level of the water in the drum, as the water will be forced upward by the violent circulation.

Under actual operating conditions, a boiler constructed as covered by my Patent No. 1,869,309, with improvements as hereafter stated, the water dropped to 28 and $\frac{1}{2}$ inches below the bottom gauge cock and 11 inches below the drum, notwithstanding which, the water from the side circulating tubes was not only sufficient to keep the drum from overheating in the fire box, but the water 11 inches below the bottom of the drum was sufficient to keep up a circulation, from which it will be seen that a construction shown in my said patent with improvements is such that it is almost impossible for a locomotive boiler so constructed to explode.

In the instance above related a few of the fire tubes collapsed, with other minor damage.

The object of my present invention is to provide an improvement in the boiler shown in my above designated patent.

One of the objects of my invention is to extend a single drum a material distance into the boiler.

Another object of my invention is to provide a

boiler extension with splash openings in the side walls.

Another object of my invention is to provide a drum extension with baffles to control the surging of the water incident to the stopping and starting of the locomotive.

Another object of my invention is to add to the number of tubes extending between the bottom headers and the top headers shown in the design of my Patent No. 1,869,309. For that purpose, in addition to employing substantially vertical water tubes connecting the top and bottom headers on the respective sides of the firebox, I also employ other sets of tubes connecting each bottom header on one side of the firebox to a top header on the other side of the firebox. Thereby the heating surface is increased, the violence of the circulation enhanced, and the safety factor improved.

Another object of my invention is to provide means for rigidly securing the steam drum extension against vibration.

Still another object is to provide suitable apertures through the drum extension walls, whereby water may be discharged from the drum over the back flue-sheet and the adjacent and underlying fire tubes in such a manner as to obviate dangerous overheating or collapse even under serious low water conditions.

With these and other objects in view, my invention consists of parts and combination of parts herein set forth.

In the drawings:

Figure 1 is a central vertical longitudinal sectional view through the center portion of a locomotive boiler constructed in accordance with my invention.

Figure 2 is a top plan view of the fire box showing the arrangement of the water tubes and their co-acting headers.

Figure 3 is a fragmentary elevation of a portion of the locomotive boiler showing more particularly the fire box and adjacent parts.

Figure 4 is a transverse vertical section on an enlarged scale taken on line 4—4 of Figure 1.

Figure 5 is a detail horizontal section taken on line 5—5 of Figure 4.

Figure 6 is a transverse vertical section taken on line 6—6 of Figure 1.

Figure 7 is a transverse vertical section taken on line 7—7 of Figure 1, the rods 10 and bridge 8 being omitted from this view.

Figure 8 is a transverse vertical section taken on line 8—8 of Figure 1.

Figure 9 is a transverse vertical section taken on line 9—9 of Figure 1.

Figure 10 is a horizontal section on an enlarged scale taken on line 10—10 of Figure 1.

Figure 11 is a sectional view on the line 11—11, Figure 1, looking in the direction of the arrows.

The reference numeral 1 designates the fire box of a locomotive having a throat sheet 2, a back head 4, and a jacket 5. The fire box may, according to practice, vary in length.

Extending centrally and longitudinally of the fire box is a single drum 6 which extends at its forward end through the back flue sheet 19a, and at its rear end through the back head.

The drum is cut on a downward and forward slope providing a major projection 6b of the same extending into the barrel 7, forward of the rear or back flue sheet 19a, said drum extension being reduced to a substantially semi-circular trough like portion adapted to readily fit in the portion of the barrel 7. This trough like portion or extension of the drum 6 extends substantially into the barrel 7, and, therefore, it becomes necessary to anchor or brace it against vibration for which purpose I provide T irons within the trough extension 6b which are secured to the side walls of the trough by means of rivets or the like 9. Gussets or baffle plates 17 are secured to these T irons. A bridge strengthening member 8 spans the interior of the drum and has its ends, which engage and conform in shape to the interior surfaces of the drum walls, suitably secured thereto by rivets 8a. One end of each of a plurality of rods 10 is suitably secured to the bridge 8, while the other end of said rods is suitably secured to another T iron 11 secured to the front flue sheet 12. Appropriate plates 13 are secured to the forward end of the trough extension 6b having ears to which one end of relatively short brace rods 16 are secured while the other ends of these rods 16 are secured to T irons 14a secured to the front flue sheet 12. Additional brace rods 16 are also secured to the front end of the trough extension and to other T irons 16a also secured to the front flue sheet 12, as shown in Figures 9 and 10.

The rods 10, 14 and 16 transmit and distribute stresses between the drum extension and the front flue sheet and check vibrations of the drum.

The upper edge portions of the drum extension 6b are secured to the sheet by means of the angle plates 6a, secured to the barrel wall and between pairs of which plates those edge portions extend.

The large bulk of water in the drum and its trough extension 6b will unless prevented surge violently in the stopping and starting, and other service movements, of the locomotive. Therefore, I have provided the trough extension 6b with baffles 17 secured to the inner face of the walls of the trough, as shown, in detail in Figure 7. I attach to the baffles 17 at the front of the extension 6b an additional baffle 17a which partially closes the front end of the extension 6b and retards the flow of water, said baffles 17a having slots 17b. These baffles act as retarders to the surging of the water. The side walls of the trough 6b are provided with "splash" openings 18, varying in size, through which water may splash from the trough 6b onto the tubes 19 to prevent overheating of the tubes when the water is getting dangerously low in the drum. As a further precaution against explosion of the boiler I provide the bottom wall of the trough 6b with a plurality of openings, or ports, 20 (three only being shown), said openings, preferably, being about three inches in diameter. These openings 20 are directly over the tubes 19. These

openings are circulating ports, and are intended to supply water from the drum to the back flue sheet and ends of the tubes in the event of low water.

It has been found that circulation of water from the side circulating tubes 21 was not only sufficient to keep the drum from overheating in the fire box end, but with water about eleven inches below the bottom of the drum a sufficient amount of water was discharged through the openings 20 to keep the flues and the flue sheet from overheating, thereby preventing an explosion. By preventing the overheating of the tubes I have eliminated the possibility of the flue sheet being forced off the tubes, and also prevented the majority of the tubes from collapsing.

The improvements disclosed herein when incorporated in the structure otherwise revealed by my Patent No. 1,869,309, will constitute a safety boiler that will not explode so long as substantial quantities of water continue to reach the drum from the tubes, even though the water falls far below the drum, which takes the place of the usual crown sheet.

To increase radiant heating surface of the boiler shown in my above patent, I have added a plurality of third tubes 22, as more clearly shown in Figures 4 and 5, which third tubes are secured in the openings 23 formed in the lower and upper headers 24, 25, respectively, but extending vertically as do the circulating tubes 21. The body portion of these additional water circulating tubes 22 extend upwardly and transversely of the fire box, the upper end of each tube 22 being in open communication with the upper header 25 at one side of the fire box, while its lower end is in open communication with the header 24 at the opposite side of the fire box, as clearly shown in Figure 4. These additional circulating tubes are so positioned relatively to each other and to the tubes 21 that they may be readily and conveniently cleaned. Connection nipples 26 connect the upper headers and the drum. The forward ends of the lower headers communicate with the water space of the barrel through the throat sheet.

The splash openings 18 and ports 20 insure a larger supply of water between the drum and the side shell of the boiler which results in a decided advantage in assisting circulation, especially to the back flue sheet, besides preventing the collapse of the tubes, and keeping the flue sheet from overheating.

What I claim is:

1. In a locomotive boiler, a cylindrical drum extending through the upper part of the firebox and having a U-shaped in cross section extension into the barrel of the boiler, the upper margins of the sides of said extension being secured to the boiler shell.

2. In a locomotive boiler, a drum in the fire box having a forward extension U shape in cross section and extending a major distance into the shell of the boiler, a back flue sheet, fire tubes extending forwardly from the back flue sheet and positioned under said extension, ports in the bottom wall of said extension positioned over said tubes, a baffle plate positioned near the rear of said extension, and a baffle plate positioned near the front end of said extension, an additional baffle plate secured to the said front baffle plate to further retard the flow of water in said extension.

3. In a locomotive boiler, a drum in the fire box having a forward extension U shape in cross

section and extending a major distance into the shell of the boiler, a back flue sheet, fire tubes extending from the back sheet and positioned under said extension, ports in the bottom wall of said extension and positioned over said tubes, a baffle plate positioned near the rear of said extension, and a baffle plate positioned near the front end of said extension having a more restricted opening than that of the said rear baffle plate to further retard the flow of water at the front end of the extension.

4. In a locomotive boiler, a drum in the fire box having a forward extension U shape in cross

section and extending a major distance into the shell of the boiler, a back flue sheet, fire tubes extending from said sheet and positioned under the said extension, ports in the bottom wall of said extension positioned over the said tubes, splash ports in the side walls of said extension, a baffle plate positioned near the rear of said extension, a baffle plate positioned near the front end of said extension and having a more restricted opening than the said rear baffle plate to further retard the flow of water at the forward end of said extension.

GEORGE H. EMERSON.
